[57] CLAIM

The ornamental design for a toy robot watch, substantially as shown and described.

DESCRIPTION

FIG. 1 is a front elevational view of a toy robot watch showing my new design;
FIG. 2 is a right side elevational view thereof;
FIG. 3 is a left side elevational view thereof;
FIG. 4 is a rear elevational view thereof;
FIG. 5 is a top plan view thereof;
FIG. 6 is a bottom plan view thereof;
FIG. 7 is a right front perspective view of the holder/strap portion with the robot-watch omitted for clarity of illustration;
FIG. 8 is a front elevational view of the robot-watch portion with the holder/strap omitted for clarity of illustration;
FIG. 9 is a right side elevational view of FIG. 8, the left side being a mirror image thereof;
FIG. 10 is a rear elevational view of FIG. 8;
FIG. 11 is a top plan view of FIG. 8;
FIG. 12 is a bottom plan view of FIG. 8;
FIG. 13 is a front elevational view of FIG. 8 with portions thereof in alternate positions;
FIG. 14 is a right side elevational view of FIG. 13, the left side being a mirror image thereof;
FIG. 15 is a rear elevational view of FIG. 13;
FIG. 16 is a top plan view of FIG. 13;
FIG. 17 is a bottom plan view of FIG. 13.
